(57)

CLAIM

The ornamental design for a machine tool for metal working, as shown and described.

DESCRIPTION

1. Machine tool for metal working

1.1 : Perspective

1.2 : Front

1.3 : Back

1.4 : Top

1.5 : Left

1.6 : Right

The bottom view is not included and forms no part of the claimed design.

The broken line in the reproductions discloses the unclaimed portion of the machine only and forms no part of the claimed design.

1 Claim, 6 Drawing Sheets(56)
